UNITED STATES PATENT OFFICE.

HENRY HELLING, OF DENVER, COLORADO.

STEAM-TRAP.

SPECIFICATION forming part of Letters Patent No. 645,506, dated March 13, 1900.

Application filed February 17, 1899. Serial No. 705,783. (No model.)

To all whom it may concern:

Be it known that I, HENRY HELLING, a citizen of the United States of America, residing at Denver, in the county of Arapahoe and State of Colorado, have invented certain new and useful Improvements in Steam-Traps; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in steam-traps, my object being to still further improve the construction set forth in my former patent, No. 610,862, dated September 13, 1898; and to these ends the invention consists 20 of the features hereinafter described and claimed, all of which will be fully understood by reference to the accompanying drawings, in which is illustrated an embodiment thereof.

In the drawings, Figure 1 is a vertical longitudinal section taken through my improved steam-trap. Fig. 2 is a fragmentary section taken on the line Y Y, Fig. 1. Fig. 3 is a section taken on the line X X, Fig. 1.

Similar reference characters indicating corresponding parts in the views, let the numeral 30 5 designate a casing which occupies a vertical position, its top being provided with an opening whereby it is adapted to be connected with the steam-pipes of a system. The bottom of this casing is closed by a head 6, which is provided with a flange engaging a flange on the bottom of the casing. The head is fastened to the casing by passing bolts through registering apertures formed in the engaging 35 40 flanges. The head 6 is provided with an opening or passage 6^a, whose outer extremity is threaded to connect with a conduit (not shown) leading to the sewer. In this bottom head is formed a central threaded opening 45 communicating with the passage-way 6^a and into which is screwed a valve-chamber 7, having a central opening into which is also screwed a plug 8, in which is formed an escape-orifice 9, through which the water passes 50 to the opening 6^a. The upper part 7^a of the valve-chamber is apertured to receive a rod or stem 10, which fits closely therein and

passes through a guide 12, formed on the interior of the chamber. Below the guide the stem 10 is provided with a stop-collar 13. The 55 lower extremity of the stem is formed into a valve 14, adapted to engage a seat 8^a, formed in the plug 8 around the top of the escape-orifice 9. The top of the valve-chamber is 60 perforated around the opening through which the valve-stem 10 passes for the admission of water from the surrounding receptacle. The upper extremity of the valve-stem is adjustably connected with the bottom of a float 15 by means of a nut 16, located in a stirrup-shaped coupling attached to the bottom of the float and adapted to screw upon the upper threaded extremity of the valve-stem.

At one side of the bottom of the casing is formed an opening 25, leading to an upwardly-projecting passage-way 17, whose upper extremity forms a junction with a passage 18, leading downwardly and connecting with the opening 6^a by way of an orifice 19, formed in the bottom 6 of the casing. Located at the 70 junction of the passage-ways 17 and 18 is a valve 20, provided with a screw-stem 21, having a hand-wheel at its outer extremity. The valve 20 is adapted to engage a seat surrounding the top of the passage 17, whereby communication between the two passages 17 and 18 is cut off when the valve is closed. This 75 valve 20 is normally closed, and the passages 17 and 18 are only utilized when it is desired to cleanse the casing of any dirt or sediment 80 that may have accumulated therein.

In using my improved device the opening in the top of the casing is connected with the lowest part of the steam system, whereby the water of condensation finds its way thereinto. 85 When there is not enough water in the casing 5 to raise the float, the valve 14 is closed. However, as the water of condensation accumulates in the casing a water seal is first formed in the bottom of the casing below the 90 float, and as the accumulation of water continues and passes up around the float the latter will be raised, thus opening the valve 14 and allowing the water to escape, first through the perforations in the top 7^a of the valve-chamber and thence through the orifice 9 to the passage-way 6^a, leading to the sewer-conduit. The waste water continues to escape 95 until the gravity of the float and its attach- 100

ments closes the valve 14 and shuts off the escape. It will be readily understood that while the valve 14 is open no steam can escape, by reason of the constant water seal in the bottom of the casing. Since the valve-chamber 7 is closed except by way of the small perforations in the top of the chamber, there is no opportunity for dirt or sediment to enter and stop the orifice 9.

10 When it is desired to clean out the casing, the valve 20 is opened and the force of the steam will drive out through the passages 17 and 18 all the sediment or foreign particles of matter that may have collected in the bottom 15 of the casing-chamber.

Having thus described my invention, what I claim is—

In a steam-trap, the combination with a re-

ceptacle connected with a steam system and arranged to receive the water of condensation therefrom, means for automatically discharging the water from the receptacle, whereby a water seal is normally maintained in the receptacle being provided with a passage leading from its bottom upwardly, and thence downwardly to an outlet-opening, and a valve located at the upper extremity of the said passage.

In testimony whereof I affix my signature 30 in presence of two witnesses.

HENRY HELLING.
